UNITED STATES PATENT OFFICE.

HUGO HILL, OF DETROIT, MICHIGAN, ASSIGNOR OF ONE-THIRD TO HERMAN SCHROETER, OF SAME PLACE.

CAR-COUPING.

SPECIFICATION forming part of Letters Patent No. 430,953, dated June 24, 1890.

Application filed March 26, 1890. Serial No. 345,242. (No model.)

To all whom it may concern:

Be it known that I, HUGO HILL, of Detroit, in the county of Wayne and State of Michigan, have invented a new and useful Improvement 5 in Car-Couplings, of which the following is a specification.

My invention consists in an improvement in car-couplings, hereinafter fully described and claimed.

10 Figure 1 is a bottom plan view. Fig. 2 is a section on line $\alpha\alpha$, Fig. 1; and Fig. 3 is an end elevation.

A represents the body of the car.

15 B C represent a device like a pair of tongs, pivoted at K to any suitable support fastened to the car and terminating at the forward ends in the arrow-heads b c.

I represents a coil-spring connecting the rear ends of B and C and drawing them together.

20 H H represent stop-pins on the inner sides of the rear ends of B and C to steady the tongs B C.

D represents a double cam pivoted on the 25 shaft L, secured to the car between the tongs B C forward of their pivot, and provided with a lever d, the end of which is connected by a chain R with the barrel of a windlass F, which windlass may be operated from the platform 30 of a passenger-car or from the top of a freight-car, or from the side of either a passenger or freight car, as desired.

E represents a ratchet-wheel on the barrel of windlass F, and G represents a spring- 35 pawl adapted to engage with the ratchet-wheel E as the tongs B C are opened, and thus prevent the closing of said tongs.

J J represent two stop-pins playing through an iron plate N, secured to the under side of 40 the car over the rear ends of the tongs B C, and normally pressed upward by the spiral springs j to permit the tongs B C to open freely.

S represents a metal plate having thereon 45 two inclined surfaces t t, lying under the stop-pins J J, and having an upturned end P, which passes through a slot n in plate N.

T represents a coil-spring which normally presses the plate S to the left, Fig. 2, so that 50 it has no effect upon the pins J J.

o represents a chain secured to the upturned

end P of the plate N and terminating in a handle or ring M.

O represents a pin projecting from the under side of the car, upon which any length 55 of the chain o may be hooked.

If the plate S be drawn to the right, Fig. 2, the inclined planes t t thereon will press the stop-pins J J outwardly, causing them to project on either side of the tongs B C and prevent 60 said tongs from opening or swinging.

The operation of my invention is as follows, and is clearly indicated by dotted lines in Fig. 1: Assuming that two cars, each provided with the device herein illustrated, are 65 to be coupled together, the arrow-heads b c are left close together on one car, and on the other car are slightly separated, so that the inner surfaces of the separated arrow-heads will strike against the outer surfaces of the 70 closed heads. The cars now being run together, the closed heads strike between and separate the slightly-separated heads, as shown by dotted lines in Fig. 1, and as soon as the heads have come together the inner 75 shoulders on the separated heads spring behind the outer shoulders on the closed heads, coupling the two cars together. The tongs B C, which are closed together, may be held rigid by drawing the plate S so as to project 80 the stop-pins J J, the chain o being hooked over the pin O to retain said pins J J in projection. When it is desired to uncouple said cars, the windlass F on the car which carries the open tongs B C is turned until said 85 tongs open wide enough to disengage their arrow-heads from the arrow-heads of the tongs of the other car, in which position they are held by the ratchet-wheel E and pawl G. On releasing the ratchet E from the pawl G the 90 spring I draws the tongs together, the double cam D swinging freely within the tongs for this purpose.

What I claim as my invention, and desire to secure by Letters Patent, is—

1. A car-coupling consisting of a pair of spring-actuated tongs terminating in arrow-heads, and a double cam journaled between the arrow-heads and the pivot of the tongs and acting by its cam-surfaces to spread the 100 arrow-heads apart, substantially as shown and described.

2. In a car-coupling, the combination, with the spring-actuated tongs B C, having the arrow-heads *b c*, of the double cam D, lever *d*, chain R, windlass F, ratchet E, and pawl D, substantially as shown and described.
3. In a car-coupling, the combination of the spring-actuated tongs B C with a double cam for spreading the tongs, and two stop-pins H, arranged, respectively, to form abutments for the two members of the tongs, substantially as shown and described.
4. In a car-coupling, the combination of the pivoted tongs B C with the spring stop-pins J J and sliding plate S, having thereon the inclined surfaces *t t*, substantially as shown 15 and described.

HUGO HILL.
